BLOWER FOR VACUUM CLEANERS

Engelbert Gorissen, Wuppertal-Barmen, Germany; Margarete Gorissen, née Becker, Wuppertal-Barmen, Germany, legal representative of Engelbert Gorissen, deceased, assignor to the firm Vorwerk & Co., Wuppertal-Barmen, Germany

Application February 20, 1936, Serial No. 64,987
In Germany March 1, 1935

1 Claim. (Cl. 230—127)

This invention relates to a blower for vacuum cleaners, in which a rapidly revolving wheel set with blades or vanes draws in air by suction, and forces it into a dust bag through an air outlet connection branching off radially or tangentially at any convenient angle of inclination to the plane of rotation of the vane wheel or fan. In blowers of this kind the fan or its vane-carrying disc has hitherto been at right angles to the axis of the fan, which has the result that the air, flowing away from the fan just at the point of connection to the air outlet branch, enters the inclined connection branch more or less in the direction of the plane of rotation of the fan, and consequently, when it impinges upon the wall thereof, it undergoes a sudden change of direction. Eddies and obstructions arising therefrom in the outflowing current of air give rise to losses of head, which considerably diminish the efficiency of the blower. The object of this invention is to obviate this disadvantage, and for this purpose the invention consists in adapting the shape of the fan to the direction of flow of the escaping air, which is determined by the inclination of the air outlet connection. This is preferably effected by raising the marginal portion of the fan or of its vane-carrying disc at the same or approximately the same angle of inclination as the air outlet connection. With such a construction of the fan the air flowing away from the fan at the place of connection of the outlet branch immediately assumes the direction of the said branch, and therefore does not undergo any change of direction in the latter. The result of this is a considerable increase in the efficiency of the blower, having regard to the quantity of air delivered, since the eddies and throttlings of the air currents, which occasion flow losses in the connecting branch, are eliminated.

Four forms of construction of the new blower, in conjunction with a manually operated vacuum cleaner, are illustrated in axial section in Figures 1 to 4 of the accompanying drawing.

In the drawing, *a* is the blower casing, with a suction nozzle or brush *b* exchangeably arranged either directly on the casing or on a separate suction connection, and an air outlet connection *c*, which branches off from the casing *a* at any convenient angle of inclination *x* to the plane of rotation of the fan or vane wheel *f*. In the manually operated vacuum cleaners illustrated, the air outlet branch *c*, to which a dust bag, not shown, is directly connected, serves at the same time as a handle. The fan, consisting of blades *f* secured to a substantially conical disc *g*, is mounted upon the shaft *e* of an electric motor

d, and is so arranged with the motor in the casing, that between the fan and the peripheral wall of the casing an air-guiding passage or diffuser *i* is obtained. The diffuser passage may extend parallel to the fan right to the air outlet connection, or else may ascend helically at an angle of inclination which is equal or approximately equal to that of the air outlet connection *c*, as shown in Figure 1.

According to the invention the shape of the fan is adapted to the direction of flow of the air discharged thereby, which is determined by the inclination *x* of the air outlet branch *c*. In the constructional examples illustrated the fan *f* or its vane-carrying disc *g* ascends uniformly towards the margin at the same angle of inclination *x*, as shown in Figure 2, or at approximately the same angle, as shown in Figure 1, as the air outlet connection *c*, as a result of which the air flowing from the fan directly into the outlet connection is from the outset directed in a direction of flow which is adapted to the angle of inclination *x* of the outlet branch.

The ascending portion of the fan disc *g* need not necessarily be rectilinear, as shown in Figures 1 and 2, but may alternatively ascend in a more or less curved line, as shown in Figure 3, or else in steps, as shown in Figure 4.

The vanes or blades *f* of the fan, on the side opposite to the carrying disc *g*, may still extend at right angles to the axis of rotation, as shown in Figures 1, 2, and 3, or else, on this side also, may be inclined upwards and outwards to a greater or less extent, as illustrated in Figure 4, to correspond to the inclination of the carrying disc.

The applicability of the invention is not restricted to the constructional forms of manually operated vacuum cleaners shown, but may equally well be applied to other types of vacuum cleaner, such as pot vacuum cleaners and the like, with the same success, in so far as the air outlet connection branches off at an inclination to the plane of rotation of the fan.

What I claim is:—

A blower for hand vacuum cleaners, comprising a casing, a substantially conical blade-carrying disc rotatably mounted in the casing, blades secured to the said disc to form a fan, and an air outlet connection branching off from the casing at an angle to the plane of rotation of the fan, the upper boundary of the inclined air outlet connection lying approximately in a continuation of the conical surface of which the blade-carrying disc forms a part.

ENGELBERT GORISSEN.
